UNITED STATES PATENT OFFICE

169,397

WEIGHING SCALE

Richard F. Straw, Rutland, Vt., assignor to The Howe Scale Company, Rutland, Vt., a corporation of Vermont

Application September 22, 1951, Serial No. 16,703

Term of patent 14 years

(Cl. D52—10)

To all whom it may concern:

Be it known that I, Richard F. Straw, a citizen of the United States and a resident of Rutland, county of Rutland and State of Vermont, have invented a new, original, and ornamental Design for a Weighing Scale, of which the following is a specification, reference being had to the accompanying drawings, forming part hereof and in which:

Fig. 1 is a front elevational view of a weighing scale showing my new design.

Fig. 2 is a top plan view.

Fig. 3 is a side elevational view from the left of Fig. 1.

Fig. 4 is a side elevational view from the right of Fig. 1.

I claim:

The ornamental design for a weighing scale, substantially as shown.

RICHARD F. STRAW.
